NOVELTY BOX

Milton Kahn, New York, N. Y., assignor to Novel-
art Mfg. Co., New York, N. Y., a firm

Application October 28, 1935, Serial No. 47,177

4 Claims. (Cl. 229—3)

This invention relates to a novelty box, and its principal object is to provide a box which while normally used as a container will simultaneously constitute a mechanical ornamentation and toy, that will impart decorativeness, pleasure, or entertainment.

Other objects and advantages will hereinafter appear.

In the accompanying drawing,—
10 Fig. 1 is a plan view showing the novelty box of this invention.

Fig. 2 is a longitudinal cross-sectional elevation of the box shown in Fig. 1.

Fig. 3 is a front elevation showing the box with 15 its hinged figure and toy disposed in an upright state.

Fig. 4 is a fragmentary view, showing a side elevation of the novelty box as it appears with its figure in the erect state shown in Fig. 3.

20 The box 1 proper consists of an oblong container 2 having a cover 3 comprising a top 4 and sides 5. To one of said sides is pasted, by a layer 6 of glue, a cardboard 7 preferably forming an integral part of a cardboard figure 8, which 25 is rendered hingeable at 9 by provision of a slit 10, whereby the figure 8 may be swung about hinge 9 and disposed either in a horizontal or lying-down state upon the top 4, or in an upright position as shown in Figs. 3, 4. The cardboard figure 8 and its integral portion 7 are of a thickness considerably greater than that of the cover-top 4, for requisite uprightness and support. At the rear side of the figure 8 is located a bracket 11 of light cardboard having a flap 12 which is 30 glued to the back of the figure, whereby said bracket may be disposed either flatly against the rear of the figure to permit the latter to lie down upon the top 4 of the box, as shown in Figs. 1, 2, or the bracket 11 may be disposed perpendicularly 35 to the figure 8 to support the latter in the upright position shown in Figs. 3, 4.

As herein illustrated, the container 2 is intended to hold sheets of letter paper 13, and during the period that the letter paper is being con-

sumed, or after it is used up, or before it is sold, the box 1 may be utilized with the figure 8 in horizontal or upright positions for display, ornamentation, as a toy, or for pleasure and entertainment.

5 Variations may be resorted to within the scope of the invention.

Having thus described my invention, I claim:—

1. A polygonal novelty box having the combination of a merchandise container, a telescopic cover for said container, a cut-out figure, a board hinged to the bottom of said figure, said board being secured to the side of said cover, and said figure depending from said hinging normally lying upon the top of said cover. 10

2. A polygonal novelty box having the combination of a merchandise container, a telescopic cover for said container, a cut-out figure, a board hinged to the bottom of said figure, said board being secured to the side of said cover whereby 20 said hinging is in registry with the intersection of the top and side of the cover, and said figure depending from said hinging normally lying upon the top of said cover. 15

3. A polygonal novelty box having the combination of a merchandise container, a telescopic cover for said container, a cut-out figure, a board hinged to the bottom of said figure, said board being secured at the side of said cover, said figure depending from said hinging normally lying upon 25 the top of said cover, and means adapted to maintain said figure in an upright position. 30

4. A polygonal novelty box having the combination of a merchandise container, a telescopic cover for said container, a cut-out figure, a board hinged to the bottom of said figure, said board being secured to the side of said cover whereby 35 said hinging is in registry with the intersection of the top and side of the cover, said figure depending from said hinging normally lying upon 40 the top of said cover, and a bracket operable to maintain the figure in an upright position.

MILTON KAHN.
